UNITED STATES PATENT OFFICE.

FRANK AUGUSTEEN, OF CHICAGO, ILLINOIS.

DESIGN FOR A CHAIR.

No. 39,409.

Specification for Design.

Patented July 7, 1908.

Application filed March 23, 1908. Serial No. 422,868. Term of patent 14 years.

To all whom it may concern:

Be it known that I, FRANK AUGUSTEEN, a subject of the Czar of Russia, and residing at Chicago, in the county of Cook and State of Illinois, have invented a new, original, and ornamental Design for Chairs, of which the following is a complete specification, reference being had to the accompanying drawings, forming part thereof.

The figure is a perspective view of a chair showing my new design.

I claim:

The ornamental design for a chair, as shown.

FRANK AUGUSTEEN.
